Primary Examiner — David Muller*Assistant Examiner* — Nathan Johnston(74) *Attorney, Agent, or Firm* — Irina Hass(57) **CLAIM**

The ornamental design for a holder, as shown and described.

DESCRIPTION

FIG. 1 is a perspective view showing a new design for a holder;

FIG. 2 is a front elevation view thereof;

FIG. 3 is a rear elevation view thereof;

FIG. 4 is a right side elevation view thereof, a left side elevation view being a mirror image thereof;

FIG. 5 is a top plan view thereof;

FIG. 6 is a bottom plan view thereof; and,

FIG. 7 is a perspective view thereof showing the holder with a cup.

The portions of the holder in FIG. 7 shown in broken lines are included to show features that form no part of the claimed design.

1 Claim, 4 Drawing Sheets(56)
